UNITED STATES PATENT OFFICE.

HEINRICH ZÜNDORF, OF BARMEN, GERMANY.

BUTTON-MACHINE.

SPECIFICATION forming part of Letters Patent No. 448,569, dated March 17, 1891.

Application filed October 30, 1890. Serial No. 369,831. (No model.)

To all whom it may concern:

Be it known that I, HEINRICH ZÜNDORF, a Prussian subject, residing at Rittershausen, in Barmen, Germany, (in Rhenish Prussia,) 5 have invented new and useful Improvements in a Machine for Making the Lower Parts of a Button with Wire Eyelets, of which the following is a specification.

This invention relates to a machine for preparing the under parts of buttons, said under parts consisting of a cap of thin metal and an eye secured to the cap. The attachment of the eye, which is formed by bending a piece of wire, is accomplished by inserting the ends 15 of the wire or legs of the eye into the cap and bending them over on the inside thereof.

In the accompanying drawings the machine is shown complete and also in detail.

Figure 1 is a vertical section along xx , Fig. 20 3. Fig. 2 is a vertical section along yy , Fig. 3. Fig. 3 is a plan view of the machine. Figs. 1^a and 1^b show a cap and also a cap united with an eye. Fig. 4 is a detail view of a portion of the disk, showing the spur for receiving the button-eye. Fig. 5 is a sectional view on the line zz , Fig. 1. Fig. 6 is a detail elevation of the wire-feeding and eye-forming devices. Fig. 7 is a central sectional view of the same. Fig. 8 is a horizontal section view of the cylinder which carries the 25 punch mechanism. Fig. 9 is a detail elevation of the punch-moving devices.

To prepare the under parts of buttons, the machine contains three parts, the first consisting of an apparatus for making the wire eyes o , Fig. 1^b, the second of a device for making the caps c , Fig. 1^a, and the last of the device by which the bending over of the legs of the eye on the inside of the cap is accomplished. The motion of these parts is obtained from the shaft W , journaled in the frame or support of the machine, and which is actuated by pulley R , Fig. 2, or, if desired, by hand or foot power.

The construction of the eye, as also the apparatus therefor, is described later on. The uniting of the eye and cap is accomplished as follows: The eye is passed from the eye-forming apparatus onto a spur d . (Shown in 45 Fig. 4 in section in face view and plan view.) This spur d projects from the edge of a disk B , which turns intermittently at equal inter-

vals in the direction of the arrow. (Shown thereon in Fig. 3.) The disk B is set into the table A of the machine. The spur d , which occupies the position 1, Fig. 3, receives the eye from the eye-forming apparatus. The disk B has its upper face flush with the top of the table A , and said disk carries six spurs d at equal distances apart. Each revolution 55 of the shaft W imparts to the disk B one-sixth of a rotation, so that the spurs d , one after another, come to the position 1. When the spur at 1 has received an eye, it is carried by the next movement to the position 60 2, the eye having its legs pointing upward and gliding past the inner edge of the recess in table A . While the disk B is at rest a cap is placed onto the eye-legs, so as to occupy the position shown in view II, Fig. 1^b. On 65 the disk B continuing to revolve the eye and cap come to the position 3, Fig. 3. At this point a descending plunger causes a partial spreading of the eye-legs, so as to bring them to the position shown in view III, Fig. 1^b. 70 Upon a further one-sixth revolution another plunger completely spreads the eye-legs, as seen in view IV, Fig. 1^b, so as to firmly unite the eye and cap. The following one-sixth revolution carries the complete under part of the 75 button to the position 5, Fig. 3, over an opening O in table A , and a flat spring or scraper N , secured to the table, scrapes the eye from the spur d , and the under part of the button, falling through the opening O , can be carried by a suitable chute to a box or receiver. 80 At 6 the spur is empty, and at 1 it again receives an eye from the eye-forming apparatus.

To the under side of the disk B is secured a shaft a , Figs. 1 and 2, which passes through 85 a thickened part of the table A , and is provided with a ratchet s , engaged by a pawl k , mounted on the lever h , fulcrumed on shaft a . A spring k' holds the pawl in engagement with the ratchet. As seen in Fig. 5, which is a section along zz , Fig. 1, the ratchet s contains 90 six teeth equal distances apart, so that the shaft a and disk B can be given one-sixth of a revolution by a corresponding movement of lever h . Said lever is held by a spring f in 95 the position shown by broken lines in Fig. 5, so that the pawl k lies directly in front of a tooth of the ratchet-wheel s , and the movement of the lever away from the stop or rest

h' is caused by a lug *u* on shaft *W*, the passage of the lug turning the lever sufficiently to move the ratchet one tooth or one-sixth of a revolution. After the lug has passed on, the 5 spring *f* brings the lever *h* back to the dotted position, Fig. 5, so that the pawl *k* passes back of the next tooth, the wheel *s* remaining stationary the while. It is thus evident that upon each revolution of the shaft *W* the disk 10 *B* is turned one-sixth of a revolution. To keep the disk securely in its recess in the table *A*, a spring *n*, Fig. 1, is arranged on shaft *a*, which draws the disk securely into its recess. Over the disk *B* the cylinder *C* is centrally arranged and supported by arm *G*. The cylinder carries the punch mechanism for punching the caps, and also guides the plungers for spreading and depressing the eye-legs. The punching mechanism (shown in Fig. 2 in 15 20 25 face view and in Fig. 9 in side elevation) consists of a punch or plunger *t*, carried by an arm *t'*, secured to the rod *g*, which can reciprocate vertically in the cylinder *C*, and of a die *b*, having a central stud or counter-punch *b'*, Figs. 2 and 3, and secured to the table *A*.

To prepare a cap I place a plate or blank, Fig. 1^a of a proper size over the die *b*, and the punch *t* is then allowed to drop onto the blank, so that the latter is forced into the die, 30 and provided by the punch *b'* with a hole for the eye-legs or shanks. The punch *t* has a proper hole for the entrance of the counter-punch *b'*. The descending force of the punch is caused by the weight *g'* on guide-rod *g*, and 35 the weight is raised by a rod *m'*, running in guides *m m'*. The upper end of this rod rests freely under the weight *g'*. The rod is raised by a bell-crank lever *i i'*, engaging the shoulder *m²* and swinging on fulcrum *e'* on standard *e*. The bell-crank lever is actuated by rod *p*, running in guide *p'* and striking against lever-arm *i'*. The free end of rod *p* rests against a raised track or elevated rim *p²* on the disk *E*, mounted on shaft *W*. This raised 40 45 50 55 60 65 70 track has a portion cut away at *p³*, Fig. 1. At one side of this cut-out the track *p²* ends abruptly and begins again at the other side with a gradual rise. When the track *p²* has been carried with its abrupt end to the rod *p*, said rod passes into the cut-out and the lever *i i'* and rod *m'* are released, so that the weight *g'* and punch *t* can drop onto die *b* and form a cap. After the passage of the cut-out *p³* the incline or gradual rise of track *p²* acts on rod *p*. This incline ends in a somewhat less elevated portion of the track, so that the punch *t* at first is only raised part way and remains a short time partly raised, during which period said punch is turned with its rod *g*, so that the center of the punch comes to rest over the position 2, Fig. 3, of disk *B*. The cap, which after its formation clings to the punch *t*, is brought by this swing of the punch into such position that the hole in the cap 75 rests directly over the shanks of the eye at 2, and then the punch *t* is entirely raised by the highest part of track *p²*, acting upon the parts

p i i' m', and said punch remains so raised until it again drops into the die. The turning of the punch from its position over the die *b* to its position over the eye at 2, Fig. 3, is effected by a lever *r*, which is so arranged that it can turn on rod *g*, but does not partake of the rise and fall of said rod. For this purpose the hub of the lever has a groove, into which enters a pin *r'*, secured to cylinder *C*, and the rod *g* has a longitudinal groove *n'*, into which enters a stud *n²* on the hub of the lever. It is thus seen that the rod *g'* must follow the rotation of lever *r*, while said rod is free to move vertically as the groove *n'* and stud *n²* form a movable connection.

To the lever *r* is connected a link *l*, united to the bell-crank lever *l' l²*, fulcrumed at *e'*. The lever-arm *l²* is connected to the rod *B*, 85 running in guide *p'* and actuated by the raised rim or track *l⁴*, located adjacent to track *p²* on disk *E*. The track *l⁴* consists only of a short elevation, which, striking the free end of rod *B*, moves the latter, so as to swing the lever *l' l²* and move link *l*, so as to turn the lever *r*. The punch *t* is thus brought into position over the die *b*, as seen in Figs. 2 and 8, which latter represents a section along *x' x'*, Fig. 2. When the raised track *l⁴* has passed 90 the rod *B*, the spring *l⁵* presses the rod forward or outward and the lever *r* moves in the opposite direction, so that the punch *t* comes to position 2, Fig. 3, or over the eye. When the punch has reached this position, it is entirely raised, as already described. To scrape off the cap from the punch on the ascent of the latter, so that the cap will fall with its hole over the shanks of the eye, the punch enters by a fork *w i*, Figs. 2 and 8, the prongs of which 95 are so arranged that they snugly clasp the punch, and thus scrape the cap off the punch as soon as the latter passes from the dotted position in Fig. 2 to its highest position.

The plungers *D F*, guided in the cylinder *C*, are intended to spread and fasten down the eye-shanks in the caps when the latter are in the positions 3 and 4, Fig. 3. These plungers must of course be accurately located over the points 3 and 4, respectively. The plungers 110 are secured to a common weight *H*, which is carried by the rod *I*, guided centrally to the cylinder. The end of plunger *D* is somewhat ground off at opposite faces, so as to be slightly sharpened to readily enter between 115 and spread the eye-shanks, and the plunger *F* has its end rounded, so that on striking the eye-shanks it will bend them over to lie firmly against the inside of the cap. The weight-carrying rod *I* is extended downward through 120 disk *B* and its shaft, and near its end said rod has a nose *T'*, which is actuated at suitable intervals by an eccentric disk *I²* on shaft *W*, so as to raise the rod, and after the high 125 part of disk *I²* has passed the nose *T'* the rod 130 and weight *H* suddenly drop.

Figs. 1 and 2 show the rod *I*, weight *H*, and plungers *D F* raised, in which position the nose *T'* is held up by a raised or high part of

disk I². When the revolution in the direction of the arrow, Fig. 1, has carried this high part past the nose I', the latter suddenly slides down and the weight H, with the plungers D E, falls, so that the latter enters between the eye-shanks, after which on the further revolution of the disk I² the plungers are again brought to the raised position, Figs. 1 and 2. The descending force of the weight H can be augmented by the spring I³, secured to the lower end of rod I and to the connecting-rod T. The tension of this spring can be regulated by the screw T'. The screw s' is secured to a side of the weight H, and on the descent of the weight the end of screw s' strikes upon the cylinder C, so as to take up the lateral jar caused by the striking of the plunger D F.

To properly fix the disk B in position after each one-sixth revolution, it is provided with six perforations, into which a rod q, Figs. 1 and 2, enters from below immediately after the passage of the arm u past the lever h and after the latter has gone back to the stop h'. For this purpose the rod q rests with its lower end on the eccentric q', mounted on shaft W. The eccentric raises the rod q at the proper moment; but as soon as the disk B is to turn the rod q sinks into a lower part of the eccentric, so as to pass out of the perforation in disk B.

The apparatus for forming the eyes has yet to be described, said apparatus being shown partly in Figs. 2 and 3 and on an enlarged scale in Figs. 6 and 7. The apparatus contains a plunger S, reciprocating along the vertical plate P, and provided at its upper end with a cutter S' for cutting off the wire and, a semicircular recess S². The levers K L swing on fulcrums M M' and carry the fingers U. The lever L has an arm L' resting on lever-arm K', against which presses a spring K², so as to separate the levers K L. The pushing arrangement V V' V², Fig. 3, pushes the completed eye from the rod Q onto a spur of disk B, and the wire is fed to the eye-forming apparatus by the rollers w, actuated by pulley w' and gear-wheels w². The pulley w' receives motion from pulley v and shaft wa, Figs. 1 and 2, and the shaft wa receives motion from the shaft W by means of pulleys v' v². The wire o', Figs. 3 and 6, for forming the eyes is fed from a suitable supply or bobbin (not shown) between the rollers w and through a suitable hole in the guide-piece S³ until it abuts against the opposite guide-piece S⁴. The pieces S³ S⁴ form a guide or way for plunger S. The portion of wire between the guide-pieces S³ S⁴ is cut by cutter S' on the ascent of plunger S, and as this piece of wire rests directly under the rod Q the rise of plunger S will cause the wall of recess S² to bend the wire about rod Q, so that the wire ends point upward, as shown in dotted lines in Fig. 6. While the wire piece so bent is in the position just named the levers K L are moved toward one another, as shown by the

arrows, Fig. 6, to bring the fingers U U together and bend the wire ends about the rod Q, so that the eye takes the form shown in view I, Fig. 1^b. For this purpose the ends of the fingers U are correspondingly formed, so that the wire ends which are pressed together pass one another—that is to say, they come to rest alongside of one another.

The eye-forming apparatus is set into a recess A', Fig. 3, of the table in such a manner that an end of rod Q is directly in front of that spur d on disk B which is at the position 1. The other end of rod Q is fastened at Q². Over the rod moves the pusher V V', formed with circular cross-section at V and four-cornered at V', said pusher being guided in a corresponding gutter V³ of the table A. The round part V passes through an inlay P' in plate P, and the free end of part V lies flush with that face of inlay P' against which the plunger S is held by spring f e. When the part V moves toward the free end of rod Q, the eye o on such rod is pushed off the rod onto the spur d of disk B. The movement of part V is caused by the actuator V² receiving motion from disk E by means of a roller ro, which enters a cam-groove E' on disk E. The actuator V² is guided by a channel or slot s i, and the slot s i' and pin do form a connection between the actuator V² and pusher part V. As soon as the roller ro enters the forward part of cam-groove E' the pusher V V' is moved forward, and when the forward part of groove E' has passed on the pusher is moved back. The plunger S and levers K L are moved, respectively, by an eccentric-disk S⁵ and an arm L² on shaft W. The eccentric-disk S⁵ strikes a lug S⁶ on plunger S, so as to raise the plunger, and when the high part of the eccentric has passed the lug S⁶ the plunger S moves back again. The arm L² acts on the arm L³ of lever L so as to cause the levers L K to move toward one another.

The co-operation of the various parts is such that at each revolution of the shaft W a wire eye is finished and fed to the disk B. At the same time the punching apparatus forms a cap and places the latter on an eye. The plungers D F bend over the eye-shanks on the interior of the cap, and the rollers w feed a fresh piece of wire to the eye-forming apparatus. To secure the proper sequence of operations, the various arms and eccentrics, as also the disk E, are properly mounted on shaft W.

The punching mechanism for forming the caps can be left out of the machine—that is, the previously-finished caps can be placed by hand on the shanks of the eye in position 2, Fig. 3. Since the putting on of the caps by hand may, however, cause a disturbance in the position of the eye on the spur d and a consequent inclination of the eye-shanks toward one side or another, the eye must be accurately righted as soon as it reaches the position 3, so that the plunger D will strike be-

tween the eye-shanks. For this purpose the machine is provided with a righting device consisting of a slide *ch*, Figs. 1 and 3, and an actuating-lever *ch'*, fulcrumed at *ch*² and actuated by a lug *ga*, Fig. 3, on disk *E*. The movement of the lever *ch'* presses the slide *ch* forward, and as the latter has a flat spring *ei*, provided with a recess *ei'*, the forward motion of the slide will right the eye, since the sides of recess *ei'* engage the eye-shanks at each side and thereby press the eye-shanks into an upright position, after which the slide is drawn back either by a spring or by a suitable cam-groove on disk *E*, made to act on lever *ch'*.

What I claim as new, and desire to secure by Letters Patent, is—

1. In a machine for attaching eyes to caps, the combination, with an intermittently-rotated disk *B* for holding the eye, of plungers *D* *F* for bending the eye-shanks over on the inside of the cap, substantially as described.
2. In a machine for attaching eyes to caps, the combination, with an intermittently-rotated disk *B* for holding the eye and plungers *D* *F* for bending over the eye-shanks on the inside of the cap, of an ejector *N* for detaching the completed article from the disk *B*, substantially as described.
3. The combination, with the machine for attaching eyes to caps, of an eye-forming ap-

paratus consisting of a plunger *S* for cutting and bending the wire, a rod *Q*, about which the wire is bent, fingers *U* *U* for bending the eye-shanks, and a pusher *V* *V'* *V*² for pushing the eye off the rod *Q*, substantially as described. 35

4. The combination, with the swinging punch *t* and die *b*, of a releasing-fork *wi*, into which the punch is swung in order to be stripped of its cap on the rise of the punch, substantially as described. 40

5. The combination, with a punch *t* and a reciprocating and rotating rod *g*, to which the punch is connected, of mechanism, substantially as described, for reciprocating and rotating the rod, and a releasing-fork for stripping the punch of its adhering article, substantially as described. 45

6. The combination, with the eye-carrying device or disk *B*, of a righting device for the eyes, said righting device consisting of a split flat spring *ei* and a slide *ch* for moving the spring toward the eye, substantially as described. 50

In testimony whereof I have hereunto set my hand in presence of two subscribing witnesses.

HEINRICH ZÜNDORF.
